UNITED STATES PATENT OFFICE.

LEWIS LAMBORN, OF HAMORTON, PENNSYLVANIA.

ROAD-SCRAPER.

SPECIFICATION forming part of Letters Patent No. 290,246, dated December 18, 1881.

Application filed June 29, 1883. (No model.)

To all whom it may concern:

Be it known that I, LEWIS LAMBORN, of Hamorton, in the county of Chester and State of Pennsylvania, herein set forth my claims 5 for Improvements in Road-Scrapers, reference being had to the accompanying drawings.

Figure 1 is a side elevation of the machine when placed on an ordinary road-wagon. Fig. 2 is a plan of the same. Fig. 3 shows one of 10 the compound levers and one of the beams by which the pressure exerted is directed to a point behind the scraper. Fig. 5 shows another method of accomplishing the same end. Fig. 4 shows the method of draft used.

15 This invention is an improvement in machines for leveling and scraping roads.

In the drawings like letters of reference refer to like parts of the machine in the different figures.

20 A is the frame placed on the running-gear of a wagon.

B B are two vertical posts attached to the frame A, and united at their lower ends by the draft-bar C. This draft-bar is connected 25 by a clevis, U, and an eyebolt, G, Fig. 3, to beams D D, which pass directly over the scraper S, and are fastened to it.

E, Figs. 1 and 3, is a compound lever, made 30 up of two longitudinal levers—one above and one below the frame—connected by a link pivoted at F" F", having its handle at H', fulcrums at F and F', and being attached to the beam D some distance behind the scraper at the point H. The lever I, Fig. 4, is similar 35 to lever E, being attached to the other beam, D. A bar, K, extends from the beam D at the point H to a point, L, near the bottom of the scraper.

40 Fig. 5 shows another method of applying pressure behind the scraper.

a is a hand-lever, with its fulcrum at b.

c is a rod extending from the lever to the beam D at a point behind the scraper. A similar contrivance may be used on the other side.

45 m m are rods connecting the pivot-bolt T with the draft-bar C. This bolt T is used to fasten the frame A to the running-gear of the wagon.

B' is a rudder attached to the scraper, by 50 which the machine may be kept in its place.

P is the guide-pole and gearing of the wagon on which the frame may be placed.

Q is a semicircular plate of metal attached to the bar W. This bar W is fastened to the frame by clips R. The plate Q rests upon the 55 bolster, some part of said plate being directly above the body-bolt of said wagon when the wagon is turned round.

Z is a link connecting the body-bolt of the wagon with the bolt T. One of these links is 60 above, one below the axle.

A' is a rod, which may be fastened, when needed, to the beam D, and above to the frame A. This is used to hold the beams and scraper in any particular position. It can be removed 65 if not needed. There is a similar rod on the other side of the machine, joining the other beam with the frame A.

By removing the body of an ordinary wagon, placing this frame A in the place of said body, 70 fastening the gearing to the frame in front by the bolt T, and clamping the frame A to the guide-pole and stays in the rear, the machine is ready for use.

There are two points in which I believe my 75 machine to be superior to all others.

First. The exertion of the power for holding the scraper down to work by means of the compound levers E and I, or the lever a and the rod c at the point H, or any convenient 80 point behind the scraper. I am aware that a rod similar to c has been used, being fastened to the top of the scraper; but this rod, being fastened to the beam D at a point behind the scraper, enables the operator to exercise more 85 direct control over and to exert greater power upon the scraper than if the rod were attached to the top of the scraper. This exertion and application of the force and power behind the scraper by any convenient means secures better 90 results than could possibly be attained by attaching the lever to the top of the scraper, (see Figs. 3, 4, and 5,) and obviates the inconvenient necessity of having heavy wheels and running-gear to hold and keep the said scraper-bar in proper position.

Second. The use of the clevis U, fitting loosely in the eyebolt G, allowing the ends of the beams D to move vertically, and giving a corresponding motion to the scraper-bar. In 95

RECORDED IN THE U. S. PATENT OFFICE, WASHINGTON, D. C., JUNE 29, 1883. (No. 290,246.)

stead, therefore, of an unyielding pressure against an obstruction, thereby jarring the whole machine, giving the horses an ugly jerk, and seriously annoying the operator, the end 5 of the beam to which the clevis is attached falls till the bar G reaches the top of the clevis U; then the bottom of the scraper falls back correspondingly, yielding to the obstruction, allowing the scraper to pass over it with no 10 jar to any part of the machine beyond said beams and scraper. The scraper not yielding in such cases and the consequent jar have been heretofore the chief objection to road-scrapers. My construction, as above set forth, 15 obviates this difficulty.

Having fully described my invention, what I claim as new, and desire to secure by Letters Patent, is as follows:

1. The combination of the beams D, the

scraper S, the clevis U, and the eyebolt G 20 with the draft-bar C and the posts B, attached to a supporting-frame, substantially as and for the purposes set forth.

2. The combination of a supporting-frame, the beams D, the clevis U, the eyebolt G, 25 the draft-bar C, and the scraper S with devices for exerting force or pressure on the beams D at some point behind the scraper, substantially as and for the purposes set forth.

3. The combination of the rods m, attached 30 to the frame by the pivot-bolt T, and the draft-bar C, with the beams D, the bars K, and the scraper S, substantially as and for the purposes set forth.

LEWIS LAMBORN.
